(57) **CLAIM**

The ornamental design for a game piece set, as shown and described.

DESCRIPTION

FIG. 1 is a front, right, top side perspective view of the first game piece of the game piece set of the claimed design; FIG. 2 is a rear, left, top side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a front, right, top side perspective view of the second game piece of the game piece set of the claimed design; FIG. 10 is a rear, left, top side perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; FIG. 16 is a bottom plan view thereof; FIG. 17 is a front, right, top side perspective view of the third game piece of the game piece set of the claimed design; FIG. 18 is a rear, left, top side perspective view thereof; FIG. 19 is a front elevational view thereof; FIG. 20 is a rear elevational view thereof; FIG. 21 is a left side elevational view thereof; FIG. 22 is a right side elevational view thereof; FIG. 23 is a top plan view thereof; FIG. 24 is a bottom plan view thereof; FIG. 25 is a front, right, top side perspective view of the fourth game piece of the game piece set of the claimed design; FIG. 26 is a rear, left, top side perspective view thereof; FIG. 27 is a front elevational view thereof; FIG. 28 is a rear elevational view thereof;

(Continued)

FIG. 29 is a left side elevational view thereof;
 FIG. 30 is a right side elevational view thereof;
 FIG. 31 is a top plan view thereof;
 FIG. 32 is a bottom plan view thereof;
 FIG. 33 is a front, right, top side perspective view of the fifth game piece of the game piece set of the claimed design;
 FIG. 34 is a rear, left, top side perspective view thereof;
 FIG. 35 is a front elevational view thereof;
 FIG. 36 is a rear elevational view thereof;
 FIG. 37 is a left side elevational view thereof;
 FIG. 38 is a right side elevational view thereof;
 FIG. 39 is a top plan view thereof;
 FIG. 40 is a bottom plan view thereof; and,
 FIG. 41 a front elevational view of the first, second, third, fourth, and fifth game pieces of the game piece set in an environment of use.
 The broken lines in the drawings depict portions of the game piece set that form no part of the claimed design.
